2,282,695

POCKET UMBRELLA

Peter Badovinac, Cleveland, Ohio

Application October 14, 1940, Serial No. 361,173

4 Claims. (Cl. 135—25)

This invention relates to pocket umbrellas and its general object is to provide an umbrella of the telescopic sectional staff type, that can be collapsed or folded to a size so that it can be conveniently carried within the pocket of the user, yet when in raised position, will give ample protection and casual collapsing or folding is practically impossible, regardless of the weather elements, due to novel means for latching the staff sections in raised position, and the particular rib structure and bracing means therefor.

A further object is to provide a pocket umbrella that can be raised and collapsed almost instantly, and the rib structure not only unfolds and folds automatically with the raising and lowering of the staff, but the sections of the latter are automatically latched and unlatched when the staff is raised and lowered.

Another object is to provide an umbrella of the character set forth that includes a hollow handle forming a container for receiving the staff, ribs and cover, and a cap is provided for the container, the cap being fixed to the outer or upper staff section and provides hand gripping means to facilitate raising and lowering the umbrella.

A still further object is to provide a pocket umbrella that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a fragmentary view of my umbrella in raised position and illustrates only two units of the ribs, for the sake of clarity.

Figure 2 is a view illustrating the staff and ribs partly collapsed or folded.

Figure 3 is a sectional view taken approximately on line 3—3 of Figure 1, looking in the direction of the arrows.

Figure 4 is a sectional view taken approximately on line 4—4 of Figure 1, looking in the direction of the arrows.

Figure 5 is a view with parts completely collapsed and secured within the handle container.

Figure 6 is a sectional view taken approxi-

mately on line 6—6 of Figure 1, looking in the direction of the arrows.

Figure 7 is a sectional view taken approximately on line 7—7 of Figure 3, looking in the direction of the arrows.

Figure 8 is a perspective view of one of the reinforcing ribs of the rib structure.

Figure 9 is an enlarged fragmentary longitudinal sectional view taken through certain of the telescopically mounted staff sections in extended position.

Figure 10 is an enlarged fragmentary sectional view illustrating the manner of unlatching or releasing the upper section from the next section below the same.

Referring to the drawing in detail, it will be noted that the staff of my umbrella is made up of a plurality of telescoping sections, and while any number of sections may be included in my umbrella, the form shown includes five, indicated by the reference numerals 1, 2, 3, 4 and 5 respectively.

The sections are shown as being square in cross section and in any event are square cornered to prevent relative rotation, and are of course hollow, as well as connected one to the other to prevent separation. For that purpose all of the sections, with the exception of the upper section 5 have inturned flanges 6 formed on opposed sides of the upper ends thereof, and all sections with the exception of the lower section 1 have outwardly directed flanges 7 struck therefrom for disposal in the path of the flanges 6 to engage the latter when the staff is raised. The flanges 7 are arranged some distance above the lower ends of the sections to provide ample overlap therefor, as best shown in Figure 7, and in order to prevent wobbling of the sections or to hold them rigid when raised, the sections 2 to 5 have outwardly directed lugs 8 at their lower ends, and which bear against the section walls, as likewise best shown in Figure 7.

The sections are held latched in extended or raised position by opposed spring clips 9 struck from two of the sides of the sections 1 to 4, for disposal in pairs, and the clips are bent at an angle to provide inturned upper end portions having beveled inner ends, with the bevel uppermost, as clearly shown in Figures 9 and 10, and for a purpose which will be later described. The inturned portions are receivable in openings or slots 10 in the sections 2 to 5, and the remaining portions of companion clips are disposed in converging relation to each other. By that structure, it will be obvious that when the sections

are raised, the inturned portions of the spring clips will be automatically seated within the slots 10, to latch the sections together, as will be apparent upon inspection of Figure 9.

Fixed to the lower end of the section 4 is a disk shaped plunger 11 mounted for slideable movement within a cylindrical hollow member 12 that not only acts as a handle, but also a container, in that the outer or lower end thereof is closed and the upper end has an inturned flange 13 formed thereon to provide abutment means for the plunger. The upper section has a cap 14 connected thereto through the medium of a stem 15 that extends into the section 5, and the latter is provided with inturned flanges 16 struck therefrom and engaged with the shoulder provided by the upper end of a head 16' formed on the lower end of the stem 15 for connection of the stem to and within the section 5 for slideable movement, as will be apparent upon inspection of Figures 9 and 10.

The lower end of the head 16' is beveled to provide opposed cam faces and each of the sections 2 to 5 have a pair of converging tongues 17 struck from the lower ends thereof to likewise provide cam faces for cooperation with the cam faces of the head 16' for forcing the spring clips 9 apart, when the cap and handle are moved toward each other, it being obvious from Figure 9 that the cam faces of the head and sections 2 to 5 will engage the beveled inner ends of the inturned portions of the clips 9 and dispose them into the path of the upper walls of the slots 10, as shown in Figure 10, and that further inward movement of the sections will cause said upper walls to engage the beveled ends of the inturned portions and move the latter out of the slots to allow complete folding or collapsing of the sections, thus it will be seen that the sections are automatically latched together, when the sections are pulled apart to their extended position and are automatically unlatched when pushed together to collapsed position.

The cap is in the form of a flat disk like knob, to facilitate raising and lowering the umbrella, and it will be obvious that the cap and container are gripped for that purpose. The cap includes a reduced lower portion for disposal within the container, with the upper portion resting upon the upper edge of the container, as clearly shown in Figure 5, and the lower portion has an annular groove 18 therein for receiving the inturned upper ends of latch arms 19 that are spring pressed and pivotally mounted upon diametrically opposite sides of the container, the latter being provided with slots for the passage of the upper ends of the arms therethrough, and the latch arms not only hold the cap in closed position, with the sections, rib structure and cover within the container, but the inturned upper ends of the arms are likewise receivable within an annular groove 20 in the plunger 11 for holding the staff in raised position and consequently the umbrella accordingly, as will be apparent upon inspection of Figure 1.

Secured to the upper ends of the sections 3, 4 and 5 are notched and annular grooved collars 21, 22 and 23 respectively, for associating the rib structure with respect to the staff, the rib structure being of course for supporting the fabric top or cover 24 that is suitably secured thereto, and the rib structure consists of any number of units 25, two of which are shown, but it will be understood that the umbrella shown consists

of 12 units, as each of the collars is formed with twelve notches, one for each rib unit.

Each rib unit includes a main upper or cover receiving rib that consists of an upper link 26, an intermediate link 27 and an outer link 28. The upper link 26 has its inner end pivotally connected to the collar 23 in the usual manner, that is by a strand of wire within the annular groove thereof, and with the link 26 movably mounted within a notch, while the outer end of the link 26 is pivoted to and between ears 29 formed on an upper bracing link 30 that terminates at its outer end into ears 31 and the inner end of the bracing link 30 is pivotally connected to the collar 22 by a strand of wire mounted in the groove thereof. The intermediate link 27 has right angle bent end portions and the upper bent end portion extends outwardly and is fixed to and between the ears 31, while the lower bent end portion extends inwardly and is fixed to and between ears 33 formed on the inner end of the outer link 28.

While the upper bracing rib consists of only one link 30 that has the ears 29 disposed slightly inwardly of the outer end thereof, the lower bracing rib consists of inner and outer links 34 and 35 respectively, the inner link being pivotally connected to the collar 21 in exactly the same manner as the links 30 and 26 and the link 34 is bent at right angles adjacent its outer end to provide an outwardly or upwardly directed portion 36 pivotally connected to and between ears 37 formed on the inner end of the outer link 35 which has its outer end pivoted to and between ears 38 formed on the outer link 28 adjacent to the inner end thereof, as clearly shown in Figure 1. A connecting link 39 is provided for the intermediate link 27 and the outer link 35, the link 39 being connected to the link 27 substantially midway its ends and to the link 35 adjacent to its inner end, there being pivot pins and spaced ears for that purpose, as shown. Each of the links may be of any desired cross sectional shape, but they are shown as being channel shape for the major portion of their length, as clearly shown in Figure 8.

The inner portion of the cap preferably has a skirt 40 formed on and depending therefrom and the skirt is notched as at 41 for receiving the inner links 26 to apply pressure thereon when collapsing the umbrella to urge the rib structure to folded position, as indicated in Figure 2 which illustrates that due to the shape of the links and their connection with each other, that when the umbrella is collapsed, the rib structure is folded so that the links 26, 30 and 34 are directed downwardly, the links 27 and 35 are directed upwardly and toward the links 26, while the links 28 are directed downwardly and toward the links 35. The links are substantially of the same length, with the exception of the connecting links 39, and of course they are of a length, so that when the rib structure is folded, as shown in Figure 2, the said structure together with the staff and the cover will readily fit within the handle container 12, when the cap is secured in closed position, as shown in Figure 5.

A strap may be provided for disposal about the cover when the rib structure is folded, to hold the parts snugly together, so as to facilitate the disposal thereof within the container.

It is thought from the foregoing description that the advantages and novel features of the invention will be readily apparent.

It is to be understood that changes may be

made in the construction and in the combination and arrangement of the several parts, provided that such changes fall within the scope of the appended claims.

What I claim is:

1. In an umbrella, a staff including a plurality of telescoping sections connected one to the other, certain of said sections being slotted, pairs of spring clips struck from certain of the sections and having inturned end portions received in the slots for automatically latching the sections in raised position, a hollow handle providing a container for housing the sections when collapsed, one end section being connected to the container for slidable movement therein, a cap for the container and being connected to the other end section, means for securing the cap in closed position, converging tongues formed on the inner ends of certain of the sections, and means mounted within the last mentioned end section and having a beveled end cooperating with the converging tongues and the upper ends of the slots for engagement with the spring clips to move the latter out of the slots for unlatching the sections when being moved to collapsed position.

2. In a pocket umbrella, a staff including square cornered telescoping upper, lower and intermediate sections, inturned flanges formed on the upper ends of the lower and intermediate sections, outwardly directed flanges formed on the upper and intermediate sections between their ends and engageable with the inturned flanges to limit outward movement of the sections, outwardly directed lugs formed on the lower ends of the upper and intermediate sections and bearing against the walls of adjacent sections for holding the sections aligned when raised, means for automatically latching the sections to each other when moved to a raised position, means for automatically unlatching the sections when moved to a collapsed position, and means secured to the lower section and providing a housing for the sections when collapsed.

3. In an umbrella, a staff including a plurality

of telescoping sections connected one to the other, means for latching the sections in raised position, means for unlatching the sections when moved to a collapsed position, a hollow handle providing a container for housing the sections when collapsed. 5 a disk shaped plunger secured to one end section and fitting and slidably mounted within the container, said plunger having a groove circumferentially arranged therein, a disk shaped cap for the container and being connected to the other end section, said cap having a groove circumferentially arranged therein, spring pressed latch arms pivotally connected to the container upon diametrically opposite sides thereof and having in- 10 turned upper ends receivable in the groove of the plunger for holding the staff extended from the container, and said inturned ends being receivable in the groove of the cap for holding the latter in closed position. 15 4. In an umbrella including a staff and foldable rib units, each unit including an upper rib consisting of upper, intermediate and outer links, the outer link being pivotally connected to the intermediate link, an upper bracing rib consisting of a single link having said upper link and said intermediate link connected thereto, a lower bracing rib consisting of an inner and an outer link pivotally connected to each other, the last mentioned outer link having its outer end pivotally connected 20 to the first mentioned outer link adjacent the inner end of the latter, a connecting link between the intermediate link and the outer link of the lower bracing rib, collars secured to the staff and having said upper link, said upper bracing rib link and said inner bracing rib link pivotally connected 25 thereto respectively, and said links being shaped to bring about downward folding movement of said upper link, said upper bracing link and said inner bracing link, upward folding movement of said intermediate link and said outer bracing link, and downward folding movement of said outer 30 link of the upper rib. 35

PETER BADOVINAC.
